UNITED STATES PATENT OFFICE.

GEORGE J. BLUM, OF CHICAGO, ILLINOIS, ASSIGNOR TO ARMSTRONG-BLUM MANUFACTURING COMPANY, OF CHICAGO, ILLINOIS, A CORPORATION OF ILLINOIS.

SPARK-PLUG

No. 889,432.

Specification of Letters Patent.

Patented June 2, 1908.

Application filed February 7, 1906. Serial No. 299,933.

To all whom it may concern:

Be it known that I, GEORGE J. BLUM, a citizen of the United States, residing at Chicago, in the county of Cook and State of Illinois, have invented certain new and useful Improvements in Spark-Plugs, of which the following is a specification.

This invention relates to the devices, commonly known as spark plugs, employed for 10 firing the charge in the cylinders of explosive engines.

One of the objects of the invention is the production of a spark plug, the action of which shall be certain and not liable to be 15 disturbed by reason of the pressure of the gases in the engine cylinder.

Another object is the provision of means for taking up wear of the contacts.

A further object is the prevention of leakage 20 of gas through the bearings of the moving parts.

The invention also relates to the further improvements in spark plugs hereinafter set forth.

25 The embodiment herein shown of the invention comprises a fixed contact, a contact carried upon a pivoted arm, a spring tending to hold the contacts together, and an electromagnet in circuit with the contacts 30 for separating them.

In the accompanying drawings, Figure 1 is a perspective view of a spark plug embodying the features of my invention. Fig. 2 is a vertical central section through said 35 plug. Fig. 3 is a similar sectional view, but taken on a plane at right angles to that of Fig. 2. Fig. 4 is an enlarged detail view of the shaft for supporting the movable contact. Fig. 5 is a detail view of a modified 40 form of the shaft.

In the present embodiment of the invention, the body portion of the spark plug consists of a spool 1 comprising the stem 2 having a T-head 3 formed integral with its 45 upper end and a T-head 4 at its lower end.

An externally screw-threaded attaching stem 5 is also formed integral with said stem for securing the spark plug to an engine cylinder. A metallic disk 6 preferably of 50 brass and having a central opening 7 and a slit 7^a connecting said opening with the periphery of the disk, is adapted to lie against the inner side of each of the T-heads 3 and 4, said disks forming the ends of the 55 spool 1. In practice, the disks 6 are placed

in position by springing the slotted portion over the stem 2. The spool 1 supports a coil 8 of magnet wire, suitably insulated from the heads 3 and 4 by disks 8 preferably of asbestos. The coil 8 is connected at its 60 outer end, by means of a contact plate 9, with a binding post 10, said binding post extending through the T-head 3 and being insulated therefrom by means of the bushing 11 of lava or other suitable material. 65 The inner end of the coil 8 is attached to a pin 12 extending vertically through an opening 13 in the lower T-head 4 and the securing stem 5. The pin 12 is insulated from said T-head and securing stem by means of 70 a lava bushing 14 fixed on said rod by means of nuts 15. A contact 16, of platinum or other suitable material, is secured to a collar 17 upon the lower end of the pin 12, and is locked in position on said pin by the 75 clamping nut 18.

The movable contact 19 is carried at the lower end of a finger 20, the upper end of which finger is fixed to a rock shaft 21 supported in openings 22 in the lower T-head 80 4, the securing stem 5 and T-head 4 being chambered at 23 for the reception of said finger. The outer ends of the shaft 21 have fixed thereto the two arms 24 of an armature 25 extending across the T-heads 3 and 4 and 85 adapted to be attracted by said T-heads when the latter are magnetized. A leaf spring 26 tends to move the armature 25 away from the T-heads 3 and 4, said spring being fixed at one end to the outer side of 90 said armature and its other end having a screw-thread engagement with a set screw 27 extending through an opening 28 in said armature and bearing against one end of the 95 T-head 3.

The rock shaft 21 comprises two screws 29 threaded into the openings 22 in the T-head 4. The screws 29 are axially perforated to receive a bolt 30. The upper end of the finger 20 also is perforated for the reception of 100 said bolt, and said finger is clamped between the inner end of the screws 29 by turning said screws by means of their square heads 31. The arms 24 of the armature 25 have openings therein through which the bolt 30 passes, and said arms are clamped tightly to the ends of the screws 29 by drawing up said bolt, which bolt engages a nut 32 brazed or otherwise secured to one of the arms 24. In 105 assembling the movable parts, the screws 29 110

are turned up until they bear against the upper end of the finger 20, which causes said screws to grip the screw-threaded walls of the openings 22, preventing their rotating freely in said openings. This pressure of the screws upon the threads in the openings 22 is relieved and the parts firmly clamped together by drawing up the bolt 30 until the screws 29 turn freely in said openings. The 10 screws 29, however, fit their screw-threaded openings 22 closely enough to prevent any escape of gas through said openings.

In Fig. 5 is shown an alternative construction of the shaft 21. It comprises two 15 screws 33 the inner threaded ends of which are adapted to enter the tubular internally-screw-threaded hub 34 of the finger 20^a. The screws 33 are caused to grip the threads within the hub 34, in order to fix the finger 20^a rigidly upon its shaft, by drawing up the bolt 35.

In use, the spark plug is attached to an engine cylinder by means of the securing stem 5, and said plug included in an electric circuit by connecting one of the battery wires to the binding post 10. The spring 26 normally holds the contacts 16 and 19 together, thus closing the circuit. A current flowing through the coil 8 sets up magnetism in the 30 T-heads 3 and 4, whereupon said T-heads attract the armature 25. The contact 19 being fixed with relation to the armature 25, the movement of said armature separates the contacts, breaking the circuit and causing the formation of a spark between said contacts. The breaking of the circuit de-energizes the electromagnet and allows the spring 26 to withdraw the armature, the pivotal movement of the armature again bringing the contacts together and thereby closing the circuit.

As the contacts 16 and 19 wear the amplitude of vibration of the armature 25 is automatically increased in a corresponding degree. The tension of the spring 26 can be regulated, according to the current used or the character of spark desired, by adjusting the screw 27. When the wear upon the contacts 16 and 19 becomes so great as to make 45 the range of movement of the armature more than is desirable, the position of the contact 19 with reference to said armature may be changed by slackening the bolt 30 and the screws 29, adjusting the position of the finger 20, and tightening said bolt and screws.

It is evident that various changes may be made in the embodiment herein shown without departing from the spirit and scope of my invention, therefore no undue limitation 60 should be understood from the foregoing detailed description.

I claim as my invention:

1. In a spark plug, in combination, an electromagnet; a fixed contact; a movable 65 contact; a finger for carrying said movable

contact; a sectional shaft between the sections of which said finger is clamped; and an armature clamped to said shaft.

2. In a spark plug, in combination, an electromagnet; a fixed contact; a movable 70 contact; a finger for carrying said movable contact; a shaft to which said finger is clamped; an armature provided with two supporting arms; and a clamping bolt extending through said arms and said shaft. 75

3. In a spark plug, in combination, an electromagnet; a fixed contact; a finger carrying a second contact; a shaft comprising two members adapted to clamp said finger between them, an armature; and 80 means for clamping said armature to said shaft-members.

4. In a spark plug, in combination, an electromagnet; a fixed contact; a finger carrying a second contact; a sectional shaft between the sections of which said finger is clamped; an armature; and a clamping bolt extending through said shaft and engaging 85 said armature.

5. In a spark plug, in combination, a body 90 portion having two alined screw-threaded openings therein; a shaft comprising two screws lying in said openings; a finger adapted to be clamped between the ends of said screws and carrying a contact; means for longitudinally compressing said screws; a stationary contact; an electromagnet in circuit with said contacts; and an armature fixed with relation to said shaft. 95

6. The combination with a body portion 100 having two alined screw-threaded openings therein, of a shaft comprising two screws lying in said openings; a member adapted to be clamped between the ends of said screws; and means for longitudinally compressing 105 said screws.

7. The combination with a body portion having two alined screw-threaded openings therein, of a shaft comprising two screws lying in said openings; a member adapted 110 to be clamped between the ends of said screws, said screws being axially perforated, and means comprising a bolt extending through said perforations for compressing said screws. 115

8. The combination with a body portion having two alined screw-threaded openings therein, of a shaft comprising two screws lying in said openings, said screws having angular heads upon their outer ends; a member adapted to be clamped between the inner ends of said screws; and means for longitudinally compressing said screws. 120

9. The combination with a body portion having two alined screw-threaded openings 125 therein, of a shaft comprising two screws lying in said openings; a member adapted to be clamped between the ends of said screws, said screws being axially perforated; a stationary contact; a contact carried by said 130

member; an electromagnet in circuit with said contacts; an armature for said electromagnet, having two arms; and a bolt passing through said arms and said screws for compressing said screws and fixing said armature with relation to said screws.

10. In a spark plug, in combination, a spool comprising a stem, an upper T-head and a lower T-head; a disk having a central opening and a slit connecting said opening with the periphery of the disk, adapted to lie against the inner side of each of said T-heads; a coil on said spool; a stationary contact; a movable contact; and an armature arranged 15 to move said movable contact.

11. A spark plug having therein a chamber which is open to the pressure within the engine cylinder, said chamber having aligned screw-threaded bearing openings in its walls; 20 a movable contact, and a shaft for supporting said movable contact, said shaft lying in said openings and being screw-threaded to correspond with the screw threads in said openings.

12. A spark plug having therein a chamber which is open to the pressure within the engine cylinder, said chamber having bearing openings in its walls; a movable finger carrying a contact; a shaft for supporting said finger comprising two sections extending 25 through said bearing openings; a bolt extending longitudinally through said shaft-sections and clamping them together; a fixed contact; an electro-magnet; and an armature for rocking said shaft.

13. In a spark plug, in combination, an electro-magnet; a shaft comprising two sections; a contact supported by said shaft; a fixed contact; an armature having two attaching arms; and a bolt extending longitudinally 30 through said shaft-sections and through said arms, and clamping said parts together.
